The ornamental design for a pair of forceps, as shown and described.

DESCRIPTION

FIG. 1 is a perspective view of a pair of forceps, showing my new design shown in an environment of use;
 FIG. 2 is an enlarged-scale perspective view of FIG. 1, except with environment removed;
 FIG. 3 is a top plan view thereof;
 FIG. 4 is a right side elevation view thereof, the left side view being mirror image;
 FIG. 5 is a bottom plan view thereof;
 FIG. 6 is an enlarged-scale (2X) front elevation view thereof;
 FIG. 7 is an enlarged-scale (2X) rear elevation view thereof;
 FIG. 8 is an enlarged-scale (4X) elevational view taken in the direction of arrows 8-8 in FIG. 4; and,
 FIG. 9 is a section view taken along line 9-9 in FIG. 2. The broken lines in FIG. 1 represent environmental subject matter that forms no part of the claimed design. The dashed lines in FIG. 8 represent a pair of break lines to show where the object is broken to save drawing space for the sake of enlargement. The short dashed lines in FIG. 9 represent cross-sectional shading and form no part of the claimed design.
